UNITED STATES PATENT OFFICE.

WILLIAM H. RYER, SR., OF PUEBLO, COLORADO.

STOVE.

1,116,742.

Specification of Letters Patent. Patented Nov. 10, 1914.

Application filed June 5, 1913. Serial No. 771,947.

To all whom it may concern:

Be it known that I, WILLIAM H. RYER, Sr., a citizen of the United States, residing at Pueblo, in the county of Pueblo and State 5 of Colorado, have invented certain new and useful Improvements in Stoves; and I do declare the following to be a full, clear, and exact description of the invention, such as will enable others skilled in the art to which 10 it appertains to make and use the same.

This invention relates to improvements in stoves.

One object of the invention is to provide a stove adapted for burning hay, straw, leaves, 15 weeds, corn stalks, coal slack and dust and all kinds of trash in a sanitary manner without making a dirt or smoke in the room and in which the fuel may be readily renewed when consumed.

20 A further object is to improve the construction of the stove shown in United States Patent No. 427,800 granted to me May 13, 1890, whereby the same is simplified and rendered more efficient.

25 With these and other objects in view, the invention consists of certain novel features of construction, and the combination and arrangement of parts as will be more fully described and claimed.

30 In the accompanying drawings: Figure 1 is a front view of my improved stove showing the top or cover section thereof in an elevated position to facilitate the removal of the body of the stove; Fig. 2 is a central vertical section of the stove with the cover in 35 closed position and the parts arranged for use; Fig. 3 is a similar view taken at right angles to Fig. 2; Fig. 4 is a horizontal sectional view taken on the line 4—4 of Fig. 1;

40 Fig. 5 is a similar view taken on the line 5—5 of Fig. 3; Fig. 6 is a similar view on the line 6—6 of Fig. 3; Fig. 7 is a plan view of the base with the body of the stove removed.

45 My improved stove comprises a body portion 1 which is preferably of cylindrical form but which may be of any suitable shape and which is preferably formed of sheet metal. The body 1 comprises a lower section 50 1^a and an upper section 1^b, fitting into the upper end of the lower section as shown. The engaging portions of the upper and lower sections of the body are riveted or otherwise securely fastened together and 55 around the upper edge of the lower section is arranged a ring or band 2 having an out-

wardly flared upper portion, said ring being preferably secured to the body by the same rivets which fasten the sections thereof together. The ring or band 2 is provided for 60 a purpose hereinafter described. In the front of the upper section of the body 1 is formed a fuel supply opening 3 which is normally closed by a hinged door 4. Also formed in the front side of the stove near the 65 lower end thereof is a clean out opening 5 which is normally closed by a door 6 having therein a draft opening 7 which is provided with a cover plate 8 as shown. The door 4 may also be provided with an opening 9 70 having a cover plate 10 as shown. Secured in the upper end of the body 1 is a bracing ring or band 11 having on its upper edge an outwardly projecting downwardly curved 75 annular flange 12.

The body 1 of the stove is supported on a base 13 which corresponds to the shape of the body of the stove and is preferably of skeleton form or has therein apertures through which the ashes discharged from 80 the bottom of the stove may pass into the ash pan or receptacle 14 secured to the lower side of the base as shown. The base 13 is supported at a suitable elevation upon legs 15 and has on its front side an extension or 85 hearth 16 in which is formed an opening 17 for removing the contents of the ash pan and which is normally closed by a plate 18 pivoted at one corner to the extension 16 as shown. In the upper portion of the sides of 90 the ash pan 14 are formed a series of draft passages 19 through which air is supplied to the burning fuel in the body of the stove as will be hereinafter described. On the rear side of the base 13 is also formed an extension 95 plate 20 the purpose of which will be herein- after described.

Secured to the inner side of the body of the stove and extending from a point a suitable distance above the base to a point 100 near the top of the body are a series of draft flues 21 which are substantially triangular or V-shape in cross section and have their edges turned outwardly to form flanges which are riveted or otherwise secured to 105 the inner side of the body as are shown. Also arranged in the body of the stove in line with the door opening 3 is a small draft flue 22, said flue comprising a lower section 22^a and an upper section 22^b. The lower 110 section 22^a of the flue is secured to the inner side of the stove and extends from a

point a suitable distance above the base to a point in line with the lower edge of the door opening 3 as shown. The upper section 22^b of the flue 22 is slidably supported 5 in any suitable manner against the upper portion of the body of the stove above the lower section 22^a and is slightly smaller than said lower section whereby the lower end of the upper section is adapted to fit, 10 into the upper end of the lower section when said upper section is in place. Secured across the edges of the upper section opposite the door opening 3 is a plate 23 which conforms to the curvature of the body and 15 is designed to cover the door opening 3; and the side edges of this plate are slidably mounted in upright guides 34 on the inner side of the stove. The lower edge of the plate 23 rests on the upper end of the lower 20 section 22^a of the flue 22 and thus supports the upper section in position on the lower section. In the plate 23 is formed a small aperture 24 which, when the door 4 of the stove is open, is adapted to be engaged by 25 the end of a poker or other instrument whereby the upper section of the flue 22 may be raised together with the plate 23 thus uncovering the door opening 3 to permit fuel to be supplied through said opening. 30 Arranged transversely through the lower portion of the body of the stove from front to rear and immediately above the base are air heating flues 25 which are preferably triangular in cross section and have their front 35 ends secured in similarly shaped openings 26 formed in the front of the body of the stove on each side of the clean out door 6 as shown. The outer ends of the flues 25 have formed thereon outwardly projecting flanges 40 which are riveted to the outer side of the body of the stove and on the inner ends of the flues are formed similar flanges which are riveted to the inner surface of the rear side of the stove as shown. The flues 25 45 preferably taper to a slight extent from their front to their rear ends so that the smaller flanged rear ends may be readily inserted through the openings in the front side of the stove. Arranged in the base 50 of the stove in line with the rear ends of the flues 25 are air conducting pipes 27 the lower ends of which extend through the base and have thereon flared or funnel shaped mouth pieces 28. The upper ends 55 of the pipes 27 are provided with elbows which pass through openings in the rear side of the stove and communicate with the rear ends of the flues 25. By thus arranging the flues 25 and the pipes 27 it will be 60 seen that cold air will be drawn into the flared ends of the pipes and conducted therethrough to the rear ends of the flues 25 through which the air passes and is heated and discharged from the front ends of the 65 flues and into the room.

The body of the stove preferably tapers slightly from its lower end upwardly for a suitable distance in order to permit the fuel which is being burned in the stove to slip down as the same is consumed. In the 70 bottom of the stove are formed main draft openings 29 which are adapted to be opened and closed by cover plates 30 arranged on the inner side of the bottom of the stove and connected with an operating rod 31 which is slidably engaged with guide brackets 32 secured to the bottom of the stove and which has its outer end projecting through the front of the stove whereby the same may be reciprocated to shift the plates 30 over and from the openings 29 whereby the latter are covered and uncovered to the desired extent. Also formed in the bottom and preferably in a plane at right angles to that of the 75 openings 29 are supplemental draft openings 33 each of which is provided with a cover plate 34, said cover plates being secured to and independently shifted by operating rods 35 which are slidably engaged with bearing brackets 36 on the bottom of the stove and which have their outer ends projecting through the sides of the stove whereby they may be readily actuated for shifting the cover plates 34 to open or close the draft openings 33 to the desired 80 extent. By providing the draft openings and the means for covering and uncovering the same as herein shown and described, it will be seen that the draft or admission of air to the burning fuel in the lower portion 85 of the stove is readily controlled. It will also be seen that by uncovering the opening on one or the other side of the stove the fire may be caused to burn more freely on one side than the other thus heating 90 this side of the stove to a greater extent for a purpose hereinafter described. In addition to the draft controlling mechanism in the bottom of the stove the draft is further controlled by dampers 37 one of which 95 is arranged in each of the flues 21 and 22. The dampers 37 are provided with handles 38 whereby the same may be turned to open the flues to a greater or less extent thus permitting more or less of the smoke 100 and gas from the fuel burning in the lower portion of the stove to pass upwardly therethrough and to the smoke discharging pipe 105 hereinafter described. Removably engaged with the top of the 110 stove is a frusto-conical shaped cover 39 on the lower end of which is formed an annular right angular flange 40 which is adapted to set into the bracing ring or band 11 in the upper end of the stove body and to form a 115 smoke and air tight engagement therewith. The cover 39 has a sliding engagement with the lower end of a smoke pipe 41 which is 120 suitably suspended or supported above the stove and which has around its lower end 125 130

an upturned flange 42 adapted to receive an inturned flange on the upper edge of the cover 39 whereby when the latter is in place on the upper end of the stove body a smoke and air tight joint is formed between the upper end of the cover and the lower end of the smoke pipe. By thus arranging the cover 39 it will be seen that the same may be slipped upwardly on the lower end of the smoke pipe to permit the body of the stove to be removed from the base and a fresh supply of fuel placed in said body or to permit an empty body to be replaced by a full body as will be understood from what follows.

15 In order to facilitate the raising and lowering of the cover 39 the latter is provided with suitable handles 43 arranged thereon as shown. Secured to the upper end of the cover is a spring catch 44 which when the cover is raised or lifted above the body is designed to engage a keeper 45 on the pipe whereby the cover is held in a raised position while the body of the stove is being removed from and replaced on the base. In 20 order to facilitate the removal and replacing of the body 1 the latter is also provided with handles 46 secured to the sides thereof as shown.

25 Arranged in the body of the stove and having a sliding engagement with the inner sides thereof is a follower plate 47 which rests on top of the fuel and by its weight serves to continually force the fuel downwardly in the body of the stove and to 30 keep the fuel in a compact condition while being consumed in the lower end of the stove. The follower plate 47 also closes the upper portion of the stove and prevents smoke and gases from passing upwardly 35 through the fuel. The plate 47 has V-shaped notches 48 formed in its edges to receive the flues 21 and 22 on which the plate slides as the same is moved upwardly or downwardly in the stove. As hereinbefore stated, the plate 47 rests on top of the fuel in the stove and moves downwardly therewith as the fuel is consumed and in order to raise the plate 47 after the fuel has been consumed or to permit fresh fuel 40 to be supplied through the door opening 3 I provide a plate raising mechanism comprising a shaft 49 which is arranged transversely through the lower portion of the smoke pipe 41 and is revolvably mounted in suitable bearings secured to the pipe as shown. Fixed on the shaft 49 within the pipe 41 is a winding drum 51 on which is adapted to be wound a plate raising chain 52 the lower end of which is connected by branch 45 chains 53 to diametrically opposite points on the plate 47 whereby when the chain 52 is wound on the drum the plate 47 will be lifted or drawn up evenly in the stove and into the lower portion of the cover in which 50 the plate is supported while the body of

the stove is being removed from and being replaced on the base. The shaft 49 is provided on one end with a crank handle 54 and has suitably connected therewith a pawl 55 which is adapted to be engaged with the 50 teeth of an annular rack 56 secured to or formed on one of the bearings of the shaft whereby the latter and the winding drum thereon are held against retrograde movement and the follower plate 47 thus supported. When the plate is in an operative position and resting on top of the fuel the pawl 55 will be disengaged from the annular rack 56 thus permitting the follower plate to 55 move down in the stove with the fuel.

Arranged in the smoke pipe above the winding drum is a damper plate 57 having an operating stem or handle 58 which projects through one side of the pipe to permit the damper to be turned to the desired position for regulating the draft through the smoke pipe.

In Figs. 1 and 2 of the drawings the smoke pipe 41 is shown as being connected by an elbow 42^a with a supporting flue 59 arranged adjacent to the rear side of the stove and having its lower end engaged with and supported by the extension 20 of the base. The upper portion of the pipe 59 extends to and is adapted to be connected with the chimney or flue of the building in which the stove is arranged. When the smoke pipe is thus arranged the flue 59 supports the latter and the cover 39 when said cover is raised in the manner described.

In the operation of my improved stove the body thereof is removed from the base in the manner described and is filled with fuel which may be straw, hay, vines, weeds, chaff, corn stalks, cobs, broom corn refuse, leaves, flax straw and chaff, stubs from man- 95 gers, coal slack and dust, mixed with litter and trash, buffalo and other chips, saw dust, peat, sage and other fine brush, cane mash, decayed wood, waste and trash from stores, offices, shops and factories, or in fact almost any waste material which can be burned. The fuel is placed in the body of the stove in a dry condition for a portion of the way 100 up and above the dry material the fuel may be and is preferably damp or even quite wet to insure the best results in the burning thereof. The fuel when thus placed in the body of the stove is closely packed after 105 which the body is replaced on the base 13 and the cover let down in operative position on the upper end of the stove. After the cover has been placed in position the follower plate is released and permitted to lower and rest on top of the fuel in the manner described so that when the fuel is lighted in the lower portion of the stove body and is consumed the follower plate gradually forces the unburned fuel downward 110 into the lower portion of the stove as here- 115

inbefore described. By providing the draft openings in the bottom of the stove the burning of the fuel is readily controlled and by uncovering the opening the ashes may be removed or permitted to drop into the ash pan or receptacle 14 arranged beneath the base. When the fuel has been consumed or it is desired to remove the body of the furnace for any purpose the draft openings 10 in the bottom thereof are closed thus preventing any ashes or dirt from falling out of the stove while the body thereof is being removed. If at any time it is desired to replenish the fuel without removing the body 15 of the stove the follower plate 47 may be raised above the door opening 3 in the manner described and fuel thrown into the lower portion of the stove through the opening 3 after the upper section 22^b of the flue 22 and 20 the plate 23 have been raised in the manner described. When a cooking or heating utensil is hung against one side of the stove and it is desired to quickly heat the same, the draft openings in the bottom of this 25 side of the stove are opened and those on the other side closed.

From the foregoing description taken in connection with the accompanying drawings, the construction and operation of the 30 invention will be readily understood without requiring a more extended explanation.

Various changes in the form, proportion and the minor details of construction may be resorted to without departing from the 35 principle or sacrificing any of the advantages of the claimed invention.

Having thus particularly described and ascertained the nature of my invention, what I claim is:

40 1. In a stove of the character described, the combination with the body thereof having a door opening, of a draft flue angular in cross section formed with two sides and made in two members telescoping with each 45 other, the lower member being secured to the inside of the body beneath said opening and the upper member being mounted at its

lower end in the lower member with its body crossing said opening, and means for closing the upper draft flue where it crosses the openings, said means being slidable with said upper draft flue to bring the latter into and out of communication with said opening. 50

2. In a stove of the character described, 55 the combination with the body thereof having a door opening, of a draft flue of substantially V-shape in cross section formed in two sections and made in two members telescoping with each other, the lower member being secured to the inside of the body beneath said opening and the upper member being mounted at its lower end in the lower member with its body crossing said opening, and an apertured plate secured to said upper flue member where it crosses said opening, said plate being slidable with said upper flue member to bring the latter into and out of communication with said opening. 60

3. In a stove of the character described, 70 the combination with the body thereof having a door opening, of a draft flue of substantially V-shape in cross section and made in two members telescoping with each other, the lower member being secured to the inside of the body beneath said opening and the upper member being mounted at its lower end in the lower member with its body crossing said opening, an apertured plate secured to the upper flue-member where it 75 crosses said opening, said plate being slidable with said upper flue member to bring the latter into and out of communication with said opening, and upright guides secured inside the stove-body at opposite sides 80 of said opening and in which the edges of said plate slide.

In testimony whereof I have hereunto set my hand in presence of two subscribing witnesses.
